UNITED STATES PATENT OFFICE.

CHARLES D. BROUYETTE, OF CINCINNATI, OHIO, ASSIGNOR OF ONE-HALF
TO FRANCIS KARR, OF HOLLAND, MICHIGAN.

SPRING BED-BOTTOM.

No. 857,324.

Specification of Letters Patent.

Patented June 18, 1907.

Application filed January 23, 1906. Serial No. 297,503.

To all whom it may concern:

Be it known that I, CHARLES D. BROUYETTE, a citizen of the United States of America, and a resident of Cincinnati, in the county of Hamilton and State of Ohio, have invented certain new and useful Improvements in Spring Bed-Bottoms, of which the following is a specification.

This invention relates to certain improvements in that class of spring-structures commonly employed for bed-bottoms, seats and the like wherein are comprised helical springs having end coils with which is connected a wire-fabric formed of intersecting wires interlocked with each other and with such end coils in such a manner as to afford means for retaining the springs in proper relative position, the wire-fabric being at the same time adapted to serve as a support for the bedding or upholstery, and the object of the invention is to provide a structure of this general character of a simple and comparatively inexpensive nature and of a compact, strong and durable construction wherein the intersecting wires are so formed and connected with each other and with the end coils of said springs as to afford a maximum of strength and rigidity in the structure while being capable of being assembled, in the manufacture of the improved structure, in a rapid and convenient manner.

The invention consists in certain novel features of the construction and combinations and arrangements of the several parts of the improved spring-structure, whereby certain important advantages are attained and the device is made simpler, cheaper and otherwise better adapted and more convenient for use in bed-bottoms, seats, and the like, all as will be hereinafter fully set forth.

The novel features of the invention will be carefully defined in the claims.

In the accompanying drawings which serve to illustrate the invention—Figure 1 is a fragmentary plan view showing one corner portion of a spring bed-bottom embodying my improvements; Fig. 2 is a fragmentary perspective view showing a portion of one of the tie-wires of the crossed-wire fabric of the spring-structure and showing certain details of the relation thereof to the end coil of one of the springs; Fig. 3 is a fragmentary sectional view taken vertically through the structure in the plane indicated by the line

a—a in Fig. 1 and showing the relations of 55 the wires of the crossed-wire fabric to the end coils of the springs, and—Fig. 4 is a sectional detail view taken in the plane indicated by line *b—b* in Fig. 1 and showing certain features of the means for supporting the 60 outer sides of the end coils of the springs of the outer rows or series in the structure from the border-wire or reinforcing-frame of the crossed-wire fabric.

As shown in these views, the improved 65 spring-structure is embodied in a spring bed-bottom of a well-known type wherein are provided helical springs 1, 1, having closed end coils 2, 2, which are interlocked as will be hereinafter explained with a crossed-wire 70 fabric comprising a border-wire or reinforcing-frame 3 of suitable strength and extended along the edges or sides of the bed-bottom, said fabric also comprising main, auxiliary and lateral tie-wires 4, 5 and 7 which are 75 extended in one direction across the top of the bed-bottom parallel with each other and have their ends bent around the border-wire or reinforcing-frame 3 as seen at 6, 6, while their intermediate portions are provided 80 with means for engaging-connection with the end coils 2, 2 of the springs, the arrangement being such that one of the tie-wires traverses one side of the end coil of each spring in the row traversed by such tie-wire, there being, 85 by this arrangement two tie-wires extended along opposite sides of the end coils of the springs of each row or series in the structure. The crossed-wire fabric also comprises transversely-extended locking or retaining wires 90 8, 8 which are extended at right-angles to the tie-wires and intersect therewith, passing centrally across the end coils of the several springs in the respective transverse rows or series, the ends of said transverse locking or 95 retaining wires being provided with loops or eyes 9, 9 bent in them and encircling the border-wire or frame 3 of the fabric in such manner as to effectively hold the said transverse wires in position, the intermediate portions of said transverse wires 8, 8 being interlocked, as will be hereinafter explained with the tie-wires and with the end coils of the springs in such a way as to lock and hold said parts securely in relation.

The arrangement of the tie-wires is such that each such wire is passed beneath one side of the end coil of each spring 1 in the

row or series traversed by such tie-wire, whereby said tie-wire is engaged for supporting-connection at two points 10, 10, beneath each such end-coil, and since each row or series of springs is traversed by two of the tie-wires, extended along opposite sides of the end coils of its springs, it will be apparent that the tie-wires are so engaged for supporting-connection with each end coil 2 at four points 10, 10, which will be distributed around the circumference of the end coil at suitable distances apart. The main and auxiliary tie-wires 4 and 5 are, by preference and as herein shown, extended in a general plane above the end coils of the springs 1, so that the bedding may ordinarily be supported out of contact with said end coils, and the main tie-wires are provided at suitable points with downwardly-bent portions 11, 11 which are extended beneath the parts 10, 10 of the end coils which have supporting-connection therewith, the parts of said main tie-wire between said downwardly-bent portions 11 being extended across above the end coils so as to interlock therewith as shown in Figs. 1 and 2. The auxiliary tie-wires 5 also have downwardly-bent portions 12, 12 which are passed beneath the portions 10, 10, of the end coils with which they are designed for supporting-connection, and are provided with upwardly-extended parts 15, 15, intermediate between said downwardly-bent parts 12, 12, the said upwardly-extended portions 15 being designed to extend above the end coils 2 of the springs traversed by such auxiliary tie-wires at points intermediate between those points 10, 10, at which said tie-wire is engaged for supporting-connection beneath said end coils 2. The lateral tie-wires 7 are extended along the edges or lateral sides of the bed-bottom adjacent to the border-wire or frame 3, and serve for connecting the outer sides of the end coils of the springs of the outer rows or series with the said border-wire or frame 3 in order to hold the parts of the structure in relation and said lateral tie-wires are also adapted for engagement at two points, 13, 13, beneath the end coils of the respective springs so that supporting-connection is thereby afforded with each such end coil at two points 10, 10. In this way it will be seen that each side of each end coil 2 is supported at two separated points 10, 10, upon one or another of the respective tie-wires 4, 5, and 7, and in assembling the improved spring-structure, the locking or retaining wires 8 are very readily engaged with opposite sides of the respective end coils so as to intersect said opposite sides of the end coils at points midway between the points 10, 10, whereat such sides of the end coils are supported upon the respective tie-wires.

As above stated, the lateral tie-wires 7, are arranged only along the lateral sides or edges of the bed-bottom, and have engage-ment only with the outer sides of the end coils of the outer lateral or edge rows or series of springs adjacent to the border-wire or frame 3 of the crossed-wire fabric, and at the intermediate portion of the bed-bottom, between said lateral tie-wires 7, the main and auxiliary tie-wires 4 and 5 are grouped in pairs, as shown in Fig. 1, so that a main tie-wire 4 is extended along one side of each end coil in one series or row of springs, while an auxiliary tie-wire 5 is extended along the adjacent sides of the end coils of the row or series of springs next adjacent. In this way the end coils in each row or series of springs will be traversed along one side by a main tie-wire 4 and along the other side by an auxiliary tie-wire 5, as will be readily understood. The main tie-wires 4 are provided, at points intermediate between those portions 11, 11, which are engaged for supporting-connection beneath the portions 10, 10, of the respective end coils, with laterally-directed elongated loops or arms 14, which are directed beneath the respective end coils and away from the same toward the end coils of the springs of the adjacent row or series, at the side thereof traversed by the corresponding auxiliary tie-wire 5, said loops or arms 14 having their members located at opposite sides of the respective locking or retaining wires 8, 8 and 95 being passed at their extremities, above the sides of the end coils at locations equi-distant between the points 10, 10, at which the respective end coils have supporting-connection with the downwardly-bent portions 12, 100 12, of the auxiliary tie-wires 5. By this arrangement, the said arms or loops 14, 14 of the main tie-wires 4 are caused to extend, at their points of intersection with the end coils, in planes beneath the intermediate upwardly-bent portions 15, 15 of the auxiliary tie-wires 5, and at their ends, said arms or loops 14 have upwardly-bent extremities 16, forming arched and elevated sockets extended above said raised intermediate portions 15 110 of the auxiliary tie-wires as seen in Figs. 1, 2 and 3, said sockets being designed to be readily traversed by the locking-wires 8, which are thereby caused to lock and retain said parts 16 and 15 of the main and auxiliary tie-wires in relation with each other and with the end coils of the springs. In this way it will be seen that the sides of the coils traversed by the auxiliary tie-wires are prevented from tilting, and as the sides of the 120 coils traversed by the main tie-wires 4 are also engaged beneath the locking or retaining wires 8 at points intermediate between the points 10, 10, whereat said coils are supported on the portions 11, 11 of the main tie-wires 4, 125 it will also be understood that the coils are effectually held from tilting at said sides also. The lateral tie-wires 7 are also provided with arms or elongated loops 17, 17, similar to the loops or arms 14 of the main tie-wires 130

4 and also located at points between those portions 10, 10, of the end coils beneath which said lateral tie wires 7 have supporting-engagement as shown at 13, but the members 5 of the loops or arms 17 of the lateral tie-wires are passed above the end coils and are directed away therefrom toward the border-wire or frame 3 of the crossed-wire fabric and have their extremities provided with narrow 10 bights 18, with which the terminal loops or hooks 9 of the locking or retaining wires 8 are engaged as shown in Figs. 1 and 4 for holding said arms or loops 17 in relation to the border-wire or frame 3. The outer parts of the 15 locking or retaining wires 8 are engaged beneath the end coils of the springs at points intermediate between those portions 10, 10 of said coils beneath which the parts 13 of the lateral tie-wires are engaged so as to interlock with said end coils between the points 20 at which the members of the arms or loops 17 are engaged above such end coils, whereby the said end coils will be securely held to the border-wire or frame of the crossed-wire 25 fabric and will thereby be held from displacement.

From the above description of my improvements it will be evident that the improved spring-structure is of an extremely 30 simple and inexpensive nature and is especially well adapted for employment in bed-bottoms, seats and the like, since it permits of securely holding the springs against displacement and is at the same time capable of 35 assemblage with a minimum of labor.

For ordinary structures, where great stress is not likely to be brought to bear on the wire-fabric, the locking-wires 8 will not be essential to bind the parts together, for the 40 reason that the interlocking of the upturned ends 16 of the loops 14 with the end coils of the springs and the intermediate upbent portions 15 of the auxiliary tie-wires, as best seen in Fig. 3, will be effective, as is clearly 45 obvious.

Having thus described my invention, what I claim and desire to secure by Letters-Patent is—

1. In a spring-structure, the combination 50 of helical springs having end coils and arranged in parallel rows and main and auxiliary tie-wires extended along adjacent sides of adjacent rows of said springs and each having, at two points, supporting-connection 55 with the end coil of each spring in the row traversed by it, the auxiliary tie-wire having, between such points of connection with each end coil, a bent portion passed vertically upward through and resting adjacent to such 60 end coil and the main tie-wire being provided with integral loops passed through the end

coils of the springs traversed by it and extended laterally from said end coils with extremities passed between the upper face of the end coils of the adjacent row of springs 65 and the lower face of the upwardly bent portions of the auxiliary tie-wire which are passed through and interlock with such end coils, said extremities of the loops having vertically-bent terminal portions engaged behind 70 said upbent intermediate portions of the auxiliary tie-wire.

2. In a spring-structure, the combination of helical springs having end coils and arranged in parallel rows, main and auxiliary 75 tie-wires extended along adjacent sides of adjacent rows of said springs and each having, at two points, supporting-connection with the end coil of each spring in the row traversed by it the auxiliary tie-wire having, 80 intermediate such points of connection with each end coil, an upwardly bent portion passed vertically through such end coil and the main tie-wire being provided with integral loops passed through the end coils of the 85 springs traversed by it and extended laterally from said end coils with extremities passed between the upper face of the end coils of the adjacent row of springs and the lower face of the upwardly bent portions of the auxiliary 90 tie-wire which are passed through such end coils, said extremities of the loops having arched or upwardly-bent terminal eyes engaged behind said upbent intermediate portions of the auxiliary tie-wire and transversely-extended locking-wires passed across 95 the structure and through the terminal eyes of said loops above but contiguous to the intermediate upbent portions of the auxiliary tie-wires. 100

3. In a spring-structure, the combination of a row of helical springs along the lateral side of the structure and provided with end coils, a border-wire adjacent to but spaced from said end coils, locking wires the ends of which have enlarged loops forming hooks 105 encircling the border-wire and a lateral tie-wire parallel with the border-wire and having at two points supporting-connection with the end coil of each of said row of springs and having, between such points of connection with the end coil, a laterally projecting loop extending through such end coil and toward but not engaging the border-wire and with its extremity engaged with the terminal loop 110 of one of the locking-wires. 115

Signed at Cincinnati, Ohio, this 6th day of January, 1906.
